[57] CLAIM

The ornamental design for a combined handgrip and brake lever unit for a walker, as shown and described.

DESCRIPTION

FIG. 1 is a rear perspective view of a combined handgrip and brake lever unit for a walker showing my new design;

FIG. 2 is a side elevational view thereof, the opposite side elevational view being a mirror image of that shown;

FIG. 3 is a side elevational view of the brake lever unit, the handgrip unit is omitted for convenience of illustration; and

FIG. 4 is an enlarged rear perspective view of FIG. 3.

FIG. 1

FIG. 2

FIG. 3

FIG. 4
